UNITED STATES PATENT OFFICE.

ABRAHAM S. JOSEPHS, OF NEW YORK, N. Y.

GUARD DEVICE.

No. 878,069.

Specification of Letters Patent.

Patented Feb. 4, 1908.

Application filed July 20, 1907. Serial No. 384,791.

To all whom it may concern:

Be it known that I, ABRAHAM S. JOSEPHS, a citizen of the United States, residing at New York, county of New York, State of New York, have invented certain new and useful Improvements in Guard Devices, of which the following is a full, clear, and exact description.

My invention relates to guard devices for jewelry, and more particularly to watch guards.

The object of my invention is to provide a guard of simple construction which may be economically manufactured, readily secured in place, and which positively prevents the removal of the watch, or other piece of jewelry to which the guard is attached, from the body of the wearer. These objects are accomplished in the manner hereinafter described, by a construction which will be more clearly understood from an explanation of the accompanying drawings, in which—

Figure 1 is a plan view of the guard, embodying the improvements of my invention; and Fig. 2 is a view showing my guard as applied to a watch in a pocket of the wearer.

My invention comprises, broadly, the construction of a safety pin with a loop or ring at the back thereof. In the drawing, 1 indicates the pin, 2 the spring, 3 the back, 4 the guard ring, and 5 the catch.

The operation is as follows: The guard is secured by the pin to the inside of the pocket, in which the watch is carried, and the watch chain passes through the loop or guard 4, as shown in Fig. 2. The wearer may remove the watch in the ordinary manner when wishing to observe the time, the slack of the chain passing through the guard ring 4. But

40 should any other person attempt to remove the watch by lifting it out of the pocket by

the chain, the watch will become engaged by the guard ring 4, and its further removal will be prevented thereby.

It is preferable to make the pin, spring, 45 back, guard ring and catch of one piece, which can readily be accomplished by bending a piece of wire in the desired form, as shown in Fig. 1.

I do not limit my invention specifically to 50 a watch guard or the particular construction shown, as it is obvious that it may be used as well as a safety appliance for any other piece of jewelry, carried in the same manner.

What I claim is—

1. In a guard device, a safety pin and a substantially circular guard ring secured to the back thereof.

2. A guard device, comprising a pin member, a spring member, a back member, a substantially circular guard ring secured to the back member, and a catch member.

3. In a device of the character described, a substantially circular ring, arms extending from each side thereof, a spring and pin at 65 the end of one arm, and a catch at the end of the other arm, adapted to be engaged by the pin.

4. A jewelry guard comprising a one-piece safety pin and substantially circular guard 70 ring.

5. A jewelry guard comprising a substantially circular ring formed in a piece of wire, the ends of the wire twisted upon themselves and extended in opposite directions, a 75 loop formed in one end and bent toward the ring, a spring formed in the other end, and a pin extending therefrom to engage the loop.
